UNITED STATES PATENT OFFICE

ALGEO J. LEGGE, OF LOS ANGELES, CALIFORNIA

UNDERGARMENT

Application filed November 11, 1930. Serial No. 494,843.

This invention relates to an improved under garment, and has for one of its principal objects the provision of an under garment, particularly for women, which is of the slip type, and which is adapted particularly for the convenience and comfort of the wearer, especially when assuming a sitting position.

One of the important objects of this invention is to provide in an under garment or slip for women, an article of clothing which will have the desired straight sides or downwardly extending edges, while at the same time affording suitable room for expansion for fullness, especially at the hips. 10
 Still another and further important object of this invention is to provide in a garment, and particularly in an under garment, means for allowing of expansion of same at points where such expansion is necessary or desired, 20 while at the same time assuring the wearer of both comfort and complete concealment, thereby avoiding embarrassment.

Other and further important objects of the invention will be apparent from the disclosures in the accompanying drawings and the following specification.

The invention, in a preferred form, is shown in the drawings and is hereinafter more fully described.

30 In the drawings:

Figure 1 is a rear elevation of the improved under garment of this invention, portions of the upper part thereof being broken away as not essential.

35 Figure 2 is a detail sectional view taken on the line 2-2 of Figure 1.

Figure 3 is a perspective view of the garment in position on a wearer, and illustrating the expansion effect for a sitting posture.

40 As shown in the drawings:

The reference numeral 10 indicates generally the body portion of an under garment, preferably one known as the slip type, having the usual shoulder straps 12 for proper support thereof. It will be noted that the garment has straight, downwardly extending sides.

In the usual garment of this type, provision must be made for a flare at the bottom 50 to allow of necessary expansion at this point,

and this is ordinarily provided for by means of a fold or pleat as shown at 14, this being accomplished by making the lower portion of the garment of a piece of cloth of greater diameter and circumference than the upper portion. The fold or pleat being made at 14 to allow for this extra circumference and also to allow spreading at this point and a flare at the bottom. The portion of the pleat shown extending above the line of stitching 16 in Figure 1 is simply doubled over as indicated in Figure 2, but the line of stitching follows the folds of the pleat.

In addition to the fold or pleat 14, there is provided a vertical slit as best illustrated at 18, this slit being formed adjacent the outer edge of the fold 14, and preferably extending from the line of stitching 16 downwardly to a point slightly above the lowermost edge of the garment, so that an opening is here afforded which opening, however, does not allow of any undue spreading of the lower edge or hem 20.

Behind the slit 18 is positioned an extra piece of cloth 22 of the same material as the remainder of the garment, this being fastened in position at its upper edge by means of the line of stitching 16 and at its lower edge by means of a line of stitching 24. This piece of cloth 22 serves to cover that portion of the body of the wearer which would be otherwise exposed when the garment is expanded and the slit 18 is opened, particularly when the wearer assumes a stooping or sitting posture somewhat as illustrated in Figure 3. It 75

will be noted that the fold 14 is also expanded, thereby allowing ample room for expansion of the garment about such portions of the wearer's anatomy which would otherwise be considerably restricted and uncomfortable in this position, or which might exercise such a strain on the ordinary garment as to split or rip the same. The vertical dotted lines in Figure 1 indicate the extent or area of the element 22.

It will be noted that there are two of the extra pieces of cloth 22 positioned in the back of the garment, these being spaced from each other as illustrated at 28, this space being preferably enlarged downwardly where-

by a somewhat additional expansion is provided for at the point most needed.

It will be noted that herein is provided a slip or other garment which is especially adapted for the comfort of the wearer, and well adapted to the use of women who do much stooping, as in housework, particularly if the wearer is of ample proportions, and which will at the same time afford the maximum of comfort and style with a minimum of inconvenience, and which will also eliminate any possibility of embarrassment through undesired splitting, ripping, or other action which might result in exposure of the person.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. An expansion garment, comprising upper and lower body portions, the lower portion being of greater diameter and circumference than the upper portion, and a fold in the lower portion to reduce the apparent circumference thereof, said fold being open from the line of stitching downwardly to the hem of the garment, said lower portion additionally having slits formed therein, said slits extending from the line of stitching to a point substantially above the hem, together with inserts behind the slits.

2. An expansion garment, comprising upper and lower body portions, the lower portion being of greater diameter and circumference than the upper portion, and a fold in the lower portion to reduce the apparent circumference thereof, said fold being open from the line of stitching downwardly to the hem of the garment, said lower portion additionally having slits formed therein, said slits extending from the line of stitching to a point substantially above the hem, together with inserts behind the slits, said inserts being fastened to the garment along their top and bottom edges.

3. An expansion garment, comprising upper and lower body portions, the lower portion being of greater diameter and circumference than the upper portion, and a fold in the lower portion to reduce the apparent circumference thereof, said fold being open downwardly to the hem of the garment, said lower portion additionally having slits formed therein, said slits extending to a point substantially above the hem, together with inserts behind the slits, said inserts being fastened to the garment along their top and bottom edges.

4. An expansion garment, comprising upper and lower body portions, the lower portion being of greater diameter and circum-

ference than the upper portion, and a fold in the lower portion to reduce the apparent circumference thereof, said fold being open downwardly to the hem of the garment, said lower portion additionally having slits formed therein, said slits extending to a point substantially above the hem, together with inserts behind the slits, said inserts being fastened to the garment along their top and bottom edges, the top edge fastening being above the uppermost limits of the slits, and the lower edge fastening being along a line substantially above the garment hem.

In testimony whereof, I affix my signature.

ALGEO J. LEGGE.
